HAROLD W. WILLIAMS, OF EAST PITTSBURGH, PENNSYLVANIA, ASSIGNOR TO WESTINGHOUSE ELECTRIC & MANUFACTURING COMPANY, A CORPORATION OF PENNSYLVANIA

INDUCTOR RELAY FOR ELEVATORS

Application filed May 11, 1927. Serial No. 190,482.

My invention relates to relays for use in control systems for controlling the operation of two or more devices which are movable with reference to each other and has special 5 application to control systems for elevator and railway cars and other similar vehicles.

One object of my invention is to provide a relay for controlling the operation of two relatively movable devices wherein no mechanical contact between the two devices is necessary.

Another object of my invention is to provide a relay for use in a control system for two relatively movable members wherein the 15 relay is actuated by magnetic cooperation between the two devices only at such times as the two devices are adjacent to each other.

Another object of my invention is to provide a relay operable to control circuits by 20 magnetic cooperation of two relatively movable members wherein the relays, having once been actuated, remain so actuated until a subsequent operation is performed.

Other objects of my invention will be apparent from the following description, taken in conjunction with the accompanying drawings, wherein:

Figures 1 and 2 are, respectively, a view in side elevation and a plan view of one form 30 of my inductor relay,

Fig. 3 is a view in side elevation, partly in section, of another form of my relay,

Figs. 4 and 5 are, respectively, a view in side elevation and a plan view of a third 35 form of my invention, illustrating the use of a plurality of circuit-controlling members operating in a predetermined sequence, and

Fig. 6 is a diagrammatic showing of the application of my relay to an elevator.

Figure 1 shows one form of my relay, wherein portions of the relay are carried by one of two relatively movable bodies and other portions by the other of said two bodies, and comprises a base 1 formed of 40 suitable insulating material on which are mounted a pair of supporting arms 2 extending laterally from the base. An electromagnet comprising a coil 3, wound upon a suitable spool or core 4 provided with end 45 discs 5 of insulating material, is mounted

between the two supporting arms 2 upon enlarged end portions 6 thereof and is secured against rotation relative to said arms by means of screws 7 projecting through each of the supporting arms into extensions 8 of 55 the end insulating discs.

To provide a suitable armature, two legs 10 and 11, formed of suitable magnetic material, are joined at their upper ends by a bar 12 of insulating material of such proportions as to rigidly connect the two legs. The armature legs 10 are rigidly secured to the ends of the core extending through the supporting members 2, to thus permit the core and armature to rotate on said members as a 60 unit. Mounted in a suitable slot 13 in the bar is a metallic contact member 14 extending rearwardly from the bar toward the base member 1. This contact member carries a 65 contact button 15, which cooperates with a stationary contact member 16 mounted upon the base, as by a screw 17. Contact member 16 carries a contact button 18.

As a means of conducting current to the movable contact member 14, a screw 19 75 mounted on the base carries at its outer end a metallic connecting member 20 which in turn is secured to the contact member 14 as by a screw 21. This connecting member or loop may be formed of flexible material so shaped 80 as to tend to bias the contact member 14 away from its cooperating contact member 16.

In this form of the device, it is readily seen that the energization of the coil 3 will cause a magnetic flux to be passed through the two 85 legs 10 and 11 of the armature, but such flux will exert no force on the armature tending to move it upon its bearings, and consequently will not cause a movement of the contact member 14. To produce a movement of the 90 contact member 14 it is necessary to bring into cooperation with the armature some magnetic influence which will exert a force at right angles to the axis of the armature. Such force may be exerted by a magnetizable 95 plate 22 or other magnetizable member when brought closely adjacent to the bent-over ends 23, 24 of the armature legs 10 and 11, respectively. As may be readily seen, the flux through the air gap A between the two 100

parts of the armature normally passes through a path of relatively high reluctance. When the magnetizable plate 22 is moved close to the armature members, the plate causes a portion of the flux passing through air gap A to be deflected through air gap B, between the plate and the armature, and a force is exerted upon the armature tending to move the same in the direction shown by the arrow. This movement will cause the contact members 14 and 16 to be brought together and close the circuit including these members, which may be any suitable control circuit for the elevator, such as a "slow down" relay circuit.

It is desirable to have the armature remain in the moved position until some subsequent operation occurs and I have, therefore, provided a holding means for the armature which comprises a pair of studs 25 and 26, formed of steel or other magnetizable material, which are mounted above the coil upon suitable supporting members 27 and 28. These studs are provided with threaded portions 29 and 30 whereby they may be adjustably secured to the supporting members. When the armature is moved under the influence of the magnetizable plate 22, the upper portions 31 and 32 of the armature legs 10 and 11 contact, respectively, with the extended portions of the studs 25 and 26, and a portion of the magnetic flux from the coil 3 passes through the armature and through these studs, traversing the air gap C between the ends of the studs. This flux creates a relatively weak force and restrains the armature member from reassuming its normal vertical position under the influence of gravity and the spring member 20. By adjusting the air gap C between the two studs, the force exerted upon the armature by this path may be varied between relatively wide limits and, in this way, the device may be made extremely sensitive to the effects of the magnetizable plate 22.

For example, in the case where the armature and coil are carried by a movable member, such as an elevator car, subjected to shocks from the unevenness of the path over which it travels, or inertia shocks caused by the starting and stopping of the member, it may be necessary to make the spring 20 relatively strong to prevent the armature vibrating under these shocks. In this case it would be necessary to exert a comparatively large force in order to hold the armature in its moved position and this result may be accomplished by suitable adjustment of the air gap between the magnetizable studs.

Figure 3 shows a slightly modified form of my device wherein an armature 40, formed of magnetizable material, having a substantially U-shaped configuration, with two end portions 41 and 42 projecting in substantially the same plane, is mounted upon suitable

bearings 43 on a supporting member 44, which in turn is mounted upon a base 45 formed of suitable insulating material. Also mounted upon this base is a support 46 for a solenoid coil 47 surrounding and enclosing the central portion of the U-shaped armature member 40. This support for the solenoid coil may be, and preferably is, adjustable as by screws 48 and 49, to permit the coil to be moved relatively to the armature member 40, for a purpose hereinafter described. The armature member carries a suitable contact member 50, which cooperates with the stationary contact member 51 mounted upon the base as by a screw 52. The operation of this form of the device is as follows:

The armature member normally assumes the position shown in the dotted lines, whereby the energization of the coil 47 exerts balancing forces upon the armature 40 to maintain it stationary. When a magnetizable plate 53 is brought adjacent to the coil and armature, the magnetic path formed between the ends 41 and 42 of the armature and the magnetizable plate 53 exerts a force tending to rotate the armature about its pivot 43, thus bringing the contact member 50 into cooperation with the stationary contact member 51 to close the circuit controlled by the relay. When the armature has been so moved, its central portion is close to the inside wall of coil 47 and will remain in this position until coil 47 is deenergized.

In this form, the sensitiveness of the relay may be varied by adjusting the position of the coil 47 with reference to the armature 40. While both forms of the relay shown in Figs. 1 to 3 are illustrated as having normally open contact members closed by movement of the armature, it is obvious that normally closed contact members could be substituted therefor.

In Figs. 4 and 5 are illustrated a circuit-controlling device operable in the same manner as the modifications shown in Figs. 1 to 3. In this latter form of the device a coil 60, shown as having an oval cross-section but which may consist of a plurality of separate coils of circular cross section has mounted thereon, as by pivots 61, a plurality of armatures 62, 63 and 64. Each of these armatures comprises a U-shaped member 65 of suitable magnetizable material, an extension 66 which projects beyond the plane of the coil and a pair of extensions 67 and 68 projecting toward a base 69 of suitable insulating material, upon which are mounted the support 70 for the coil and a stationary contact member 71. Upon the extension 67 of the armature member is mounted a contact member 72 cooperating with the stationary contact member 71. Upon the other of the extensions 68 is adjustably mounted, as by a screw 73, one end of a spring 74, the other end of which is secured to the upper end of the core of the

coil as at 75, this spring normally tending to pull the two contact members into engagement. A suitable cover member 76 of non-magnetizable material is shown as fastened by a screw 77 to one end of the coil supporting member 70 and extending upwardly over the upper ends of the armature member. The function of this cover member 76 is to form an enclosure for the coil and the operating parts of the relay and at the same time act as a stop device limiting the movement of the armature under the influence of the coil. A striker button 78 is illustrated as taking the shock of contact between the armature and the cover and is also utilized for maintaining the armature operated once it has been picked up.

As may be readily seen from an inspection of Fig. 5, the illustrated magnetizable plate 79 formed of sections of varying width, is so mounted that each of the sections cooperates respectively, with one of the armature members of the relay as the car passes. Thus, as the armature members and the coil are moved in the position indicated by the arrow, the left hand armature 64 will be the first to be brought adjacent the magnetizable plate and, as the coil and armature continue downwardly, the central and right hand armatures will successively be brought adjacent the other sections of the magnetizable plate. The three sets of relay contact members will thus be opened in a predetermined sequence.

This form of the device is especially useful in connection with the stopping of elevators accurately at floor levels. For example, by connecting the high speed relay to the contact members of armature 64, the intermediate speed relay to those of the armature 63 and the slow speed relay to those of the armature 62, the car will be brought to an accurate stop at the landing by successive steps of slowing down and stopping the elevator motor.

Fig. 6 shows an arrangement of the relays of the type shown in Figs. 1 and 2 for producing a similar result. In this figure, guides 80 and 81 are shown as provided in the elevator shaft, upon which the elevator car 82 is moved upwardly and downwardly by cables. Disposed upon the top, or any other suitable portion of the elevator car 82 is a mounting structure 83, shown as being formed of sections of angle iron braced in a suitable manner, as by a bracing member 84. Upon this structure a plurality of relays 85, 86 and 87, of the type shown in Fig. 1, are mounted at varying heights above the top of the elevator for cooperation with an elongated magnetizable plate 88 mounted upon suitable supports upon the wall of the hatchway. As the car comes down the shaft the relay 85 will first be brought adjacent the magnetizable plate 88, then relay 86 and finally relay 87 will be brought adjacent to the

plate 88. The distances between the several relays will, of course, depend upon the rapidity with which the car decelerates when the several speed switches are deenergized, and the position at which the last of the relays 70 is brought adjacent the magnetizable plate will, of course, depend upon the position of the plate with respect to the floor.

Other suitable applications of my relay may be made, for example, the three relays 75 illustrated in Fig. 6 may be actuated by a single short magnetizable plate and yet maintain the proper timing of the sequence of operations, by connecting the coil of relay 86 to be closed only after the preceding relay 85 80 has been actuated and allowing relay 87 to close only after relay 86 has closed. This application is obvious and I have not deemed illustration thereof to be necessary here.

It is thus seen that I have provided a relay 85 which is especially adapted for use with elevator and railroad cars and other vehicles wherein accurate control of the vehicles may be had without mechanical contact between the vehicles and the tracks or paths over 90 which the vehicles travel.

The several forms of my device shown in the drawings are preferred forms but are merely illustrative of the essentials of my invention and are not to be considered as limiting my device to the forms shown herein except as defined by the appended claims.

I claim as my invention:

1. In a relay, an armature, energizable means for magnetizing said armature, independently movable means cooperating magnetically with said armature when magnetized by said coil for imparting movement thereto, circuit-controlling means operable by movement of said armature, and means 100 for holding said armature, when so moved, during the energization of said energizable means.

2. In a relay, an armature, energizable means for magnetizing said armature, independently movable means cooperating magnetically with said armature when magnetized by said coil for imparting movement thereto, circuit-controlling means operable by movement of said armature, means for holding said armature, when so moved, during the energization of said energizable means, and means for restoring said armature to normal position when said energizable means is deenergized.

3. In a relay, an energizable coil, an armature, means for mounting said armature for energization by said coil, a magnetizable plate movable with respect to said armature, for causing said coil to move said armature when energized by said coil when said armature and said plate are adjacent each other, circuit-controlling means operable by movement of said armature, and means for maintaining said armature in the posi- 130

tion to which it is moved while said coil is energized.

4. In a relay, an energizable coil, an armature, means for mounting said armature and said coil for relative movement, said coil when energized being normally ineffective to move said armature, magnetizable means movable with respect to said armature for magnetic cooperation therewith when said magnetizable means and said armature are adjacent for rendering said coil effective to cause movement of said armature, and means rendered effective by movement of said armature for holding said armature in the position to which it is moved during energization of said coil.

5. In a relay, a movable armature, energizable means for magnetizing said armature, magnetizable means movable with reference to said armature and said first-named means for magnetic cooperation therewith to cause movement of said armature when magnetized by said coil, circuit-controlling means operable by movement of said armature, and means for maintaining said armature in its new position during energization of said energizable means.

6. In a relay, a coil, an armature, means for mounting said coil and said armature for relative movement from a normal to an abnormal position, said coil being normally ineffective to move said armature when energized, magnetizable means movable with reference to said armature and coil for rendering said coil effective to move said armature to said abnormal position when said coil and said magnetizable means are adjacent to each other, said coil being rendered effective to hold said armature so moved, and circuit-controlling means operable by movement of said armature.

7. In a relay, a coil, an armature comprising two legs, means for mounting said legs on said coil rigidly with respect to each other and movable with respect to said coil, means for energizing said coil to magnetize said armature with a different polarity for each leg, a magnetizable plate movable with reference to both said legs for causing the magnetic force in said legs to produce a relative movement of said armature and said coil, circuit-controlling means operable by movement of said armature, and means rendered effective by movement of said armature for maintaining said armature in its moved position during energization of said coil.

8. In a relay, a coil, an armature comprising two legs, means for mounting said legs on said coil rigidly with respect to each other and movable with respect to said coil, means for energizing said coil to magnetize said armature with a different polarity for each leg, a magnetizable plate movable with reference to both said legs for causing the magnetic force in said legs to produce a relative move-

ment of said armature and said coil, circuit-controlling means operable by movement of said armature for maintaining said armature in its moved position during energization of said coil, and means for conducting current to a part of said movable armature and for restoring said armature to normal when said coil is deenergized.

9. In a relay, a coil, an armature comprising two legs, means for mounting said legs on said coil rigidly with respect to each other and movable with respect to said coil, means for energizing said coil to magnetize said armature with a different polarity for each leg, a magnetizable plate movable with reference to both said legs for causing the magnetic force in said legs to produce a relative movement of said armature and said coil, circuit-controlling means operable by movement of said armature, and adjustable means rendered effective by movement of said armature for maintaining said armature in its moved position during energization of said coil.

10. In an inductor relay, a coil, a core for said coil, an armature comprising two legs, means for mounting said core and said legs for unitary movement relative to said coil, means for energizing said coil to magnetize said armature with a different polarity for each leg, a magnetizable plate, movable relative to said armature for causing the magnetic force in said legs to produce a relative movement of said armature and said coil, and circuit-controlling means operable by movement of said armature.

11. In a relay, an armature, a coil for energizing said armature, means for mounting said armature and said coil for relative in movement, said coil when energized being normally ineffective to move said armature, magnetizable means movable with respect to said armature for magnetic cooperation therewith when said magnetizable means and said armature are adjacent for causing movement of said armature when energized by said coil, and adjustable means rendered effective by movement of said armature for holding said armature in the position to which it is moved during energization of said coil.

12. In a relay, an armature, a coil for energizing said armature, means for mounting said armature and said coil for relative movement, said coil when energized being normally ineffective to move said armature, magnetizable means movable with respect to said armature for magnetic cooperation therewith when said magnetizable means and said armature are adjacent for causing movement of said armature when energized by said coil, means rendered effective by movement of said armature for holding said armature in the position to which it is moved during energization of said coil, and means for adjustably limiting the movement of said armature.
